(57) **CLAIM**

The ornamental design for a combination bottle and cap with L-shaped handle, as shown and described.

DESCRIPTION

FIG. 1 is a perspective view of a first embodiment of a combination bottle and cap with L-shaped handle showing our new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top view thereof;

FIG. 7 is a bottom view thereof;

FIG. 8 is a perspective view thereof, showing the handle in an alternate position of use;

FIG. 9 is a front elevational view thereof;

FIG. 10 is a rear elevational view thereof;

FIG. 11 is a right-side elevational view thereof;

FIG. 12 is a left-side elevational view thereof;

FIG. 13 is a top view thereof;

FIG. 14 is a bottom view thereof;

FIG. 15 is a perspective view of a second embodiment of a combination bottle and cap with an L-shape handle;

FIG. 16 is a front elevational view thereof;

FIG. 17 is a rear elevational view thereof;

FIG. 18 is a right-side elevational view thereof;

FIG. 19 is a left-side elevational view thereof;

FIG. 20 is a top view thereof;

FIG. 21 is a bottom view thereof;

FIG. 22 is a perspective view thereof, showing the handle in an alternate position of use;

FIG. 23 is a front elevational view thereof;

FIG. 24 is a rear elevational view thereof;

FIG. 25 is a right-side elevational view thereof;

FIG. 26 is a left-side elevational view thereof;

FIG. 27 is a top view thereof; and,

FIG. 28 is a bottom view thereof.

The broken lines below the bottle neck are shown for the purpose of illustrating parts of the article that form no part of the claim. The broken lines immediately adjacent the shaded surfaces form boundaries of the claim and form no part thereof.
